(57) **CLAIM**

We claim the ornamental design for an edible fruit product in the shape of a seahorse, as shown and described.

DESCRIPTION

FIG. 1 is a perspective view of the edible fruit product in the shape of a seahorse, showing our new design.

FIG. 2 is a top plan view of the fruit product of FIG. 1.

FIG. 3 is a front side view of the fruit product of FIG. 1.

FIG. 4 is a rear side view of the fruit product of FIG. 1.

FIG. 5 is a left side view of the fruit product of FIG. 1; and, FIG. 6 is a right side view of the fruit product of FIG. 1.

The fruit product is shown broken apart to indicate that no specific thickness is claimed.
